US0D1059027S

(12) **United States Design Patent** (10) **Patent No.:** **US D1,059,027 S**
(45) **Date of Patent:** **** Jan. 28, 2025**

(54) **LANYARD**

(71) Applicant: **Shenzhen City Saihui Electronics Co., LTD**, Shenzhen (CN)

(72) Inventor: **Tao Pan**, Guangdong (CN)

(73) Assignee: **Shenzhen City Saihui Electronics Co., LTD**, Shenzhen (CN)

(**) Term: **15 Years**

(21) Appl. No.: **29/900,212**

(22) Filed: **Aug. 17, 2023**

(51) LOC (15) Cl. **03-05**

(52) U.S. Cl.

USPC **D3/215**

(58) **Field of Classification Search**

USPC D3/207, 208, 212, 215, 318, 327;
